PENNSYLVANIA

MINING MACHINE

Application filed October 31, 1930. Serial No. 492,540.

The present invention relates particularly to that type of mining machines in which an endless chain cutter is employed for undercutting purposes.

The primary object of the present invention is to provide an apparatus that is very simple in construction, is very light in weight and compact, as a consequence of which it can be used in small mines, is readily handled, and requires a relatively small amount of power to operate, making it possible to be driven from storage batteries, so that it may be used in isolated places where an electrical power line is not available.

15 The preferred embodiment of the invention is illustrated in the accompanying drawings, wherein:

Figure 1 is a side elevation of the machine.

Figure 2 is a vertical longitudinal sectional view.

Figure 3 is a horizontal sectional view.

Figure 4 is a detail cross sectional view on the line 4-4 of Figure 2.

Figure 5 is a detail perspective view of the 25 top plate for the arm.

Figure 6 is a perspective view of the core frame for the arm.

Figure 7 is a detail perspective view of one 30 of the reinforcing plates.

Figure 8 is a perspective view of the sprocket wheel carrier employed at the outer end of the arm.

Figure 9 is a bottom perspective view of the ball race member for the thrust bearing.

35 Figure 10 is a perspective view of the anti-friction roller cage.

Figure 11 is a perspective view of the journal box for the said cage.

40 Figure 12 is a detail perspective view of one of the pick-carrying links.

Figure 13 is a perspective view of the spindle for the outer sprocket wheel.

Figure 14 is a detail view of one of the draft or winch wheels showing the parts separated.

45 In the structure disclosed a main body frame is employed, consisting of a brass plate 15 and a top plate 16 made of relatively heavy sheet or plate metal and separated by spacer sleeves 17. Through these sleeves pass tie

bolts 18 that secure the plates 15 and 16 together.

Projecting from the rear end of the body is an arm designated generally by the reference numeral 19. This arm has a core frame 20 consisting of longitudinal bars 21 connected by cross bars 22. The frame may be a single piece casting or otherwise suitably constructed. On the under-face of this frame is secured a bottom plate 23, and to the upper face of the frame is secured a top plate 24, these plates being elongated and extending not only beyond the ends of the frame 20, but also beyond the sides thereof, as shown in Figure 4, thereby producing guideways 25 in the opposite side edges of the arm.

The inner end of this arm 19 extends into the space between the base and cap plates 15 and 16 of the body, and interposed between said inner end of said arm and said plates 70 are strengthening plates 26. This assembly is suitably secured together by rivets 27 or other appropriate fasteners. As a consequence it will be noted that while the base plate 15 of the body rests upon the ground, 75 the arm is held a slight distance above the same. An exceedingly light but nevertheless strong frame-work is provided for the cutting mechanism.

Mounted on the central portion of the cap 80 plate 16 of the body is a suitable electric motor 28 that may be of any desired character, but is preferably reversible. It is controlled by a suitable switch 29 mounted thereon. An angular bracket 30, secured to the top plate. Journalized in this bracket is a vertical drive shaft 31 that extends downwardly through the cap plate 16, through the upper reinforcing plates 26, and the top plate 24 85 of the arm. This shaft 31, as shown particularly in Figure 2, passes through a journal box 32 bolted, as shown at 33, to the top plate 16. In said journal box is a roller bearing 90 cage with rollers 34 that bear against the shaft and the interior of the box 32. Mounted on said box is a race-way 35 in which are balls 36 borne upon by a wear washer 37. The washer 37 has resting on it the hub 38 of a bevel gear 39 keyed to the shaft and in 100

mesh with another bevel gear 40 on the motor shaft 41. There is thus provided not only a roller bearing for the shaft 31, but an anti-friction thrust bearing also.

Mounted on the lower end of the shaft 31 between the inner ends of the plates 23 and 24 is a sprocket wheel 42. Another sprocket wheel 43 is mounted at the outer or rear end of the arm 19. For this purpose a substantially U-shaped carrier frame 44 is slidably mounted between the outer ends of the plates 23 and 24 and beyond the core frame 20. In this carrier 44 is located a spindle 45 on which the sprocket wheel 43 is journaled. The ends of the spindle are angular and are engaged in openings in the top and bottom of the carrier 44 and said angular ends project into elongated guideways 46 formed in the top and bottom plates 23 and 24. A cap piece 47 is preferably secured to the upper end of the spindle 45 and overlies the upper slot 46. In order to adjust the carrier 44 and the sprocket wheel 43 and hold the same when adjusted, a threaded shank 48 is secured to the rear end of the carrier and slidably passes through an opening 49 in the adjacent cross bar 22 of the core frame 20. A nut 50, threaded on this shank 48, and bearing against the cross bar 22, serves to act as means for forcing the carrier outwardly or rearwardly of the arm and hold it against return movement. The top plate 24, as shown particularly in Figures 2 and 5, has an opening 51 giving access to the nut 50.

An endless cutter chain passes around the sprocket wheels 42 and 43 and has its side stretches operating in the guideways or grooves 25 formed by the side extensions of the plates 23 and 24 beyond the longitudinal bars 21 of the core frame (see Figure 4). This chain consists of heavy links 52 having outstanding portions 53 provided with transverse sockets 54 to receive the picks 55 which are held in place by vertically disposed set screws 56 that are located outside the edges of the top and bottom arm plates 23 and 24, so that they are entirely available. The heavy links 52 are connected by sets of lighter links 57 which serve to complete the chain.

Mounted on the rear end of the top frame behind the motor 28 is a winch. The mounting consists of a pair of brackets 58 in which is a horizontal transversely disposed shaft 59. On the central portion of this shaft, between the brackets 58, is fixed a ratchet wheel 60 adapted to be held against rotation in one direction by a pawl 61. A hand lever 62 has a forked end 63 fulcrumed on the shaft 59, on opposite sides of the ratchet wheel 60, and in the fork is mounted a pawl 64 that operates on said ratchet wheel 60. The ends of the shaft 59 project beyond the sides of the cap plate 16 and have secured thereto chain-links engaging draft wheels. As shown these

draft wheels consist of separable heads 65 with an interposed washer 66. The inner sides of the heads are serrated or pocketed as shown at 67, so as to inter-engage with the links of draft chains 68 that extend alongside the body and arm and are adapted to have their rear ends suitably secured, as indicated at 69. In order that these chains may pass around the greater part of the circumference of the draft wheels, idler rollers 70 are journaled on brackets 71 suitably secured to the brackets 58.

It will be understood that this machine is employed as are mining machines of this type. The motor 28 driving the vertical shaft 31, thereby rotates the sprocket wheel 42 and operates the chain cutter. The tautness of this chain cutter can be maintained by the longitudinal adjustment of the sprocket wheel 43, which, as already explained, is mounted in a movable carrier that is moved and held by the nut 50 on the shank 48. To advance the machine it is only necessary to operate the hand lever 62. By reason of the structural features set forth the apparatus is very light in weight and yet is strong to resist the strains and stresses that may be brought against it. It is compact and can be readily transported from place to place and employed in confined spaces. Moreover the structure permits the use of a low powered motor so that if occasion arises, the apparatus can be operated from storage batteries.

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any of the advantages of the invention.

What we claim, is:

1. In a mining machine, the combination with a body having spaced upper and lower plates, of an arm projecting from the body and also comprising spaced upper and lower plates, the plates of the arm and of the body being lapped and secured together, a vertical shaft journaled in the lapped portions of the body and arm plates, a motor geared to the shaft, and a cutter chain mounted on the arm and actuated by the shaft.

2. In a mining machine, the combination with a body having spaced upper and lower plates, of an arm projecting from the body and comprising a core and upper and lower plates respectively covering the upper and lower sides of the core and extending beyond the side margins thereof to form side channels along opposite sides of the arm, said arm plates having their rear ends extending between the body plates and secured thereto, a vertical shaft extending through the body

and arm plates and having a sprocket wheel between the rear ends of said arm plates, another sprocket wheel journaled between the outer ends of the arm plates, and a cutter chain extending around the sprocket wheels and operating in the side channels of the arm.

3. In a mining machine, the combination with a body, of an arm projecting therefrom, said arm including a core, top and bottom plates covering the upper and lower sides of the core and having projecting ends, said projecting ends having longitudinal guideways, an upright spindle slidable in the guideways, a sprocket wheel mounted on the spindle between the plates, means interposed between the spindle and core for adjusting said spindle in the guideways and thereby adjusting the sprocket wheel, a cutter chain that passes around the sprocket wheel, and means on the body for driving the cutter chain.

4. In a mining machine, the combination with a body, of an arm projecting therefrom, said arm including a core, top and bottom plates covering the upper and lower sides of the core and projecting beyond the sides of the same forming side channels, said plates also projecting beyond the outer end of the core and having longitudinal guideways in its projecting ends, a carrier frame slidably mounted between said projecting ends, an upright spindle mounted in the carrier frame and having its ends slidable in the guideways, a sprocket wheel mounted on the spindle within the carrier frame, a cutter chain operating in the side channels and about the sprocket chain, and means on the body for driving the cutter chain.

In testimony whereof, we affix our signatures.

LOUIS M. WELD.
JOHN H. OHLER.
